UNITED STATES PATENT OFFICE.

WILLIAM P. ROBERTSON, OF NEW YORK, N. Y., ASSIGNOR TO LYDIA B. KOCH, OF NEW YORK, N. Y.

CONTROL-SWITCH FOR CINEMATOGRAPHIC TARGETS.

1,351,443.

Specification of Letters Patent. Patented Aug. 31, 1920.

Application filed June 7, 1919. Serial No. 302,530.

To all whom it may concern:

Be it known that I, WILLIAM P. ROBERTSON, a citizen of the United States, residing at the borough of Manhattan, in the city, 5 county, and State of New York, have invented certain new and useful Improvements in Control-Switches for Cinematographic Targets, of which the following is a specification, reference being had therein 10 to the accompanying drawings, which form a part thereof.

My invention relates to control switches for cinematographic targets and more particularly to those details of construction by 15 which the various switches controlling the different circuits in the target structure, may be associated in compact form and will indicate the working conditions of the circuits in and about said target.

20 Cinematographic targets include therein different independently controlled circuits by means of which the mechanisms for performing different functionings of the apparatus are operated. Under some working conditions all of these mechanisms are functioning, while under other conditions the target may be operated while some of these mechanisms are inactive. For example, the motor for rewinding the paper or other web forming the screen, is controlled entirely independently of the light circuit for illuminating the openings through the screen, and the circuit actuating the timer for controlling the dwell or stationary interval of the 25 film, which mechanisms are also independent of each other. Such targets also usually contain a manually operative cut-out in the circuit to the projector motor, so that the duration of the still image upon the screen 30 may be prolonged at the will of the operator.

In a switch control made in accordance with my invention, all of the switch mechanisms are closely associated in a single switch box and are so constructed that the 35 switch levers will indicate to the operator the exact working conditions about the apparatus, the switch proper being completely concealed and protected by the housing.

The various switch mechanisms are also 40 so mounted as to be held against displacement in the housing while being capable of being separately and quickly removed therefrom to facilitate repairs or permit the sub-

stitution of a new switch for a defective one.

55 My invention does not relate to the switch mechanism proper, but merely to the manner of supporting such a mechanism and the actuating lever therefor in relation to the housing and to other such mechanisms.

60 The invention consists primarily in a switch control for cinematographic targets embodying therein a housing containing a plurality of independent switch mechanisms embodying therein a casing and a slidable 65 switch actuating member mounted therein and projecting through opposite sides thereof, a forked retaining member straddling each of said casings and detachably connected with said housing, and a forked 70 actuating lever pivotally mounted in said forked member with the arms thereof arranged on opposite sides of each of said casings in the operative relation to said switch actuating member, whereby each of 75 said casings is firmly held in relation to said housing and any of said casings may be removed from said housing independently of the others; and in such other novel features 80 of construction and combination of parts as are hereinafter set forth and described, and more particularly pointed out in the claims hereto appended.

85 Referring to the drawings,

Figure 1 is a horizontal section through a switch control mechanism made in accordance with my invention;

Fig. 2 is a front view of said mechanism;

Fig. 3 is a plan view of a portion of the housing and the switch mechanisms therein contained removed from its support, with the actuating handles removed, said view being upon an enlarged scale;

Fig. 4 is a section on the line 4-4 of Fig. 3 the plate below the actuating handle being omitted; and

Fig. 5 is a detailed view of the blank from which the retaining plates are formed.

Like letters refer to like parts throughout the several views.

100 In the embodiment of my invention shown in the drawings, *a* indicates the supporting structure for a formed up metal housing *b* containing the switch mechanisms, said housing having end and side flanges *b'* by 105 means of which it may be secured to said

support, and suitably arranged outlet openings b^2 . The housing is open at the top, this open top being closed by means of an escutcheon plate c also detachably secured to the support a . The plate c has a plurality of slots c' therein and carries various plates c^2 adjacent said slots respectively, indicating different circuits in a target apparatus.

The top edge of the housing b is provided with a plurality of inturned lugs b^3 by means of which the various switch mechanisms are assembled in the housing in a manner which will be hereinafter described.

The dimensions of the housing are such as to permit the assembling therein of a plurality of independent switch mechanisms. Since the construction and arrangement of each of said mechanisms and the manner of mounting it in said housing is identical to every other, a detailed description of but one of these mechanisms will be entered into.

The switch mechanisms employed are of the ordinary push-through type, the contacts being arranged within a casing d having slidably mounted therein and projecting through the opposite walls thereof, an actuating member d' . This type of switch is old and well known in the arts, and no claim of invention as to the specific mechanisms thereof, is made.

The ends of the casing d adjacent the outlets, are preferably reduced and squared for a purpose which will hereinafter appear.

Each casing d is secured in position in the housing b by means of two forked plates e and f each formed from a sheet metal blank like that shown in Fig. 5 of the drawings. The opening in the fork of said plates is rectangular so as to have a sliding fit with the squared end of its casing d , and the top thereof is so bent as to provide an overhang e' — f' provided with openings by means of which the plate may be secured to the housing b by being screwed to the lugs b^3 at the top of said housing. Directly opposite the opening of the fork of the plate e or f is a bearing lug e^2 or f^2 extending at substantially right angles to the top flange e' or f' , and connected therewith by a reduced extension e^3 or f^3 , by means of which lug the actuating lever g is pivotally mounted in the proper relation to the actuating member d' of the switch, the extensions e^3 — f^3 affording the proper clearance for the movement of said lever.

The actuating lever g is a forked member, the arms g' and g^2 of which extend between the retaining plates e — f and straddle the casing d , the ends of said arms being provided with projecting studs g^3 and g^4 adapted to operatively engage the actuating member d' upon opposite sides of said casing. Said lever g is provided with a screw stud g^5 by means of which the operating handle g^6 may be applied thereto. The lever g

projects through the slot c' in the escutcheon plate c , the openings in said plate c being sufficiently large to permit the removal of the plate for the purpose of affording access to the switch housing b .

The construction heretofore described permits each of the switch units to be mounted within the housing b entirely independently of the others, and consequently the removal of any unit without disturbing any of the remaining units. In assembling the switch structure, the housing b is permanently connected with the support a by means of the flange b' , with the open top thereof exposed through an opening in said support. The various wires may then be inserted through the outlet openings b^2 and connected to the switch mechanisms within the casings d in the usual manner.

The casing d is then inserted in the housing b and the forked plates e — f positioned with the forks straddling the squared ends of the casing d . Before thus positioning the retaining plates, the lever g is assembled in relation thereto by means of the pivot screw h so that in positioning these plates in relation to the casing d , the same operation will bring the forked arms g' — g^2 upon opposite sides of the casing d with the studs g^3 — g^4 in the proper relation to the actuating member d' . When the parts are in this relation, the plates e and f are secured to the lugs b^3 carried by the housing b , thus not only accurately positioning the plates with relation to the outlet openings b^2 , but holding the casing d firmly against any displacement. The various switch units in the housing b are assembled and secured in like manner.

When all of the units have been thus assembled in the housing b , the escutcheon plate c is mounted upon the support a , thus closing the top of said housing, excepting for the openings c' therein necessary to permit the desired movement of the various levers g and the mounting or dismounting of said plate c .

In the event that any switch mechanism gets out of order, access may be had to the housing b by merely removing the plate c , thus exposing all of the switch mechanisms and permitting any of them to be removed from the housing by merely disconnecting the plates e and f of the retainer for that switch from the inturned lugs b^3 , which may be quickly accomplished without disturbing any of the other units.

After repairs are effected, the switch mechanism may be reassembled in the structure in the manner above referred to, or a new switch mechanism may be substituted for a defective one with equal rapidity.

While the mechanism is in use, the position of the various lever handles g^6 will indicate the working condition of the circuit

controlled by the switch actuated thereby, the normal tendency of these handles to drop downwardly being counteracted by the spring of the switch. It will be observed 5 that the actuating lever g is a free swinging lever having no springs acting thereon except that of the switch mechanism proper, the engagement of the studs g^3 — g^4 with the opposite ends of the switch actuating member d' maintaining the switch lever in a position determined by that of said actuating member.

It is not my intention to limit the invention to the precise details of construction 15 shown in the accompanying drawings, it being apparent that such may be varied without departing from the spirit and scope of the invention.

Having described the invention, what I 20 claim as new and desire to have protected by Letters Patent, is:—

1. A switch control for cinematographic targets embodying therein a housing containing a plurality of independent switch 25 mechanisms each embodying therein a casing and a slideable switch actuating member mounted therein and projecting through opposite sides thereof, forked retaining members straddling said casings respectively and detachably connected with said housing, and forked actuating levers pivotally mounted between said forked members respectively with the arms thereof arranged on opposite sides of each of said casings in the operative relation to the switch 30 actuating member carried thereby, whereby each of said casings is firmly held in relation to said housing and any of said casings may be removed from said housing independently of the others.

2. A switch control for cinematographic targets embodying therein a housing containing a plurality of independent switch mechanisms each embodying therein a casing and a slideable switch actuating member mounted therein and projecting through opposite sides thereof, a plurality of oppositely disposed forked plates straddling opposite sides of each of said casings, each of 45 said plates having an overhang by means of which it may be secured to said housing, and a bearing lug offset with relation to said plate by a reduced extension affording clearance between said overhang, and forked 50 actuating levers pivotally mounted between said bearing lugs adjacent each casing with the arms thereof arranged on opposite sides of said casing in the operative relation to the switch actuating member carried thereby, whereby each of said casings is firmly held in relation to said housing and any of said casings may be removed from said housing independently of the others.

3. A switch control for cinematographic 55 targets embodying therein a housing hav-

ing outwardly directed end and side flanges, a plurality of inturned lugs and a plurality of outlet openings, said housing containing a plurality of independent switch mechanisms each embodying therein a casing and a slideable switch actuating member mounted therein and projecting through opposite sides thereof, a plurality of oppositely disposed forked plates straddling opposite sides of each of said casings, each of said 70 plates having an overhang by means of which it may be secured to said housing, and a bearing lug offset with relation to said plate by a reduced extension affording clearance between said overhang, and forked 75 actuating levers pivotally mounted between said bearing lugs adjacent each casing with the arms thereof arranged on opposite sides of said casing in the operative relation to the switch actuating member carried thereby, whereby each of said casings is firmly held in relation to said housing and any of said casings may be removed from said housing independently of the others.

4. A switch control for cinematographic 80 targets embodying therein a housing open at the top and having outwardly directed end and side flanges, a plurality of inturned lugs, and a plurality of outlet openings, said housing containing a plurality of independent 85 switch mechanisms each embodying therein a casing and a slideable switch actuating member mounted therein and projecting through opposite sides thereof, a plurality of oppositely disposed forked plates straddling opposite sides of each of said casings, each of said plates having an overhang by means of which it may be secured to said housing, and a bearing lug offset with relation to said plate by a reduced extension affording clearance between 90 said overhang, and forked actuating levers pivotally mounted between said bearing lugs adjacent each casing with the arms thereof arranged on opposite sides of said casing in the operative relation to the switch actuating member carried thereby, whereby each of said casings is firmly held in relation to said housing and any of said casings may be removed from said housing independently of the others, and a removable 95 escutcheon plate closing the open top of said housing.

5. A switch control for cinematographic 100 targets embodying therein a housing containing a plurality of independent switch mechanisms each embodying therein a casing and a slideable switch actuating member mounted therein and projecting through opposite sides thereof, a plurality of oppositely disposed forked plates straddling opposite sides of each of said casings, each of 105 said plates having an overhang by means of which it may be secured to said housing, and a bearing lug offset with relation to said plate by a reduced extension affording clearance between said overhang, and forked actuating levers pivotally mounted between said bearing lugs adjacent each casing with the arms thereof arranged on opposite sides of said casing in the operative relation to the switch actuating member carried thereby, whereby each of said casings is firmly held in relation to said housing and any of said casings may be removed from said housing independently of the others, and a removable 110 escutcheon plate closing the open top of said housing.

120

125

130

said plate by a reduced extension affording clearance between said overhang, and forked actuating levers pivotally mounted between said bearing lugs adjacent each 5 casing with the arms thereof arranged on opposite sides of said casing, said arms respectively having projecting studs extending into the operative relation to the switch actuating member of the casing, whereby 10 each of said casings is firmly held in relation to said housing and any of said casings

may be removed from said housing independently of the others.

In witness whereof I have hereunto affixed my signature this 24th day of May, 15 1919, in the presence of two subscribing witnesses.

WILLIAM P. ROBERTSON.
